UNITED STATES PATENT OFFICE.

THOMAS DOYLE, OF CHICAGO, ILLINOIS.

DESIGN FOR A COMBINATION LAMP AND LOUD SPEAKER.

Application filed July 1, 1927. Serial No. 22,639. Term of patent 3½ years.

To all whom it may concern:

Be it known that I, THOMAS DOYLE, a citizen of the United States, residing at Chicago, in the county of Cook and State of Illinois, have invented a new, original, and ornamental Design for a Combination Lamp and Loud Speaker, of which the following is a specification, reference being had to the accompanying drawing, forming a part thereof.

I claim:

The ornamental design for a combination lamp and loud speaker, substantially as shown.

THOMAS DOYLE.
